EXTRACTION PROCESS

David R. Merrill, Long Beach, and Philip Subkow, Los Angeles, Calif., assignors to Union Oil Company of California, Los Angeles, Calif., a corporation of California

Application October 24, 1932, Serial No. 639,343

14 Claims. (Cl. 196—13)

This invention relates to a process for the production of lubricating oil. More specifically it relates to a process for the production of lubricating oil from petroleum by the use of solvents. One of the distinctive characteristics of a lubricating oil is its viscosity. Its usefulness as a lubricant depends, at least in part upon its viscosity. For many purposes lubricants are desired whose viscosity will vary as little as possible with variations in temperature, i. e., have low temperature viscosity susceptibilities. Those fractions which exhibit a low temperature viscosity susceptibility are oftentimes referred to as the paraffinic oils whereas the fractions which exhibit a high temperature viscosity susceptibility are referred to as the non-paraffinic oils. The heavy oil fractions of many crude oils, from which lubricating oils are produced consist of a mixture of hydrocarbons some of which exhibit a low temperature viscosity susceptibility and some of which exhibit a high temperature viscosity susceptibility. In order to produce superior lubricating oil from hydrocarbon mixtures as described above, those oils present having a high viscosity temperature susceptibility are separated from the oils present which exhibit a low temperature viscosity susceptibility. Solvent extraction is one of the methods employed to separate the undesirable oil from the desirable oil. Solvents, such as aniline, furfural, nitrobenzene, selenium oxychloride, sulphur dioxide or B' B' dichlorethyl ether are capable, under the proper conditions of temperature and pressure, of dissolving the fractions present which are non-paraffinic in character.

with solvent which is less contaminated with non-paraffinic fractions. The oil entering the extraction system is contacted with solvent containing a relatively high concentration of non-paraffinic fractions whereas the purified oil is finally contacted with pure solvent. In this manner the maximum degree of refinement is usually obtained because at the final stage of the extraction relatively pure oil is contacted with fresh solvent which has a high selective solvent power to reparate the paraffinic and non-paraffinic fractions because it is not contaminated with non-paraffinic oil. When continuous countercurrent extraction is employed the extraction step may be carried out in one stage wherein the solvent and oil flow countercurrently or it may be carried out in a plurality of stages wherein the extracts obtained from the later stages of the process are returned to the earlier stages of the process and employed therein as the extracting medium. Thus in the first extraction stage the oil to be extracted is contacted with solvent containing dissolved fractions from a later stage. The insoluble oil portion in the first stage passes to the second stage where it is contacted with solvent containing less of the extracted fractions. The insoluble oil from the second stage passes successively in the same manner as described above, to the remaining extraction stages until it reaches the final stage wherein it is extracted with pure solvent. In processes of this character the same temperature is employed throughout the system and as final products there are obtained a fraction consisting largely of the non-paraffinic fractions and a fraction which is in the main com-

4.3 paraffinic in character. These solvents form relatively heavy solutions with the non-paraffinic oil fractions and can be separated from the insoluble paraffinic oil fractions by settling. The separated paraffinic oil fractions or raffinates and non-paraffinic oil fractions or extracts dissolved in solvent are then distilled to separate the solvent from the oil. The paraffinic fractions may then be given such further treatment as necessary to remove any remaining impurities. The non-paraffinic oil fractions being relatively valueless are utilized as fuel or as cracking stock in conversion processes.

4.4 The separation of hydrocarbon mixtures into paraffinic and non-paraffinic fractions by the use of solvents is not restricted to batch operation but may be carried out in a continuous manner. Where continuous extraction is employed it is customary to flow the solvent counter-currently to the oil to be extracted. Hence the oil being purified is progressively being contacted

4.5 with the non-paraffinic oil fractions and a raffinate which is the mixture composed of the paraffinic fractions.

4.6 We have found it desirable to extract oil containing hydrocarbons of the paraffinic and non-paraffinic type, with a solvent, in a plurality of stages in which fresh solvent is added in each successive stage and to separate from each stage a raffinate and solvent containing dissolved fractions. The solvent containing dissolved fractions is cooled to a temperature sufficiently low to cause the most insoluble fractions present to be forced out of solution. This mixture is then passed into a decanting chamber where the insoluble fractions, owing to their relatively low specific gravity rise to the top of the settling chamber, are removed therefrom and introduced into the lower zone of the next succeeding column. The solvent and dissolved fractions introduced into the settling chamber have a relatively high specific gravity and readily settle out. This fraction is introduced into the intermediate zone

4.7 45 50 55 55

of the next succeeding extraction column or as a further modification the solvent and dissolved fractions may be divided into two streams. One stream may be introduced into the intermediate zone of the next succeeding extraction column and the other stream may be returned to the intermediate zone of the preceding extraction column from which it was obtained. After extracting an oil to produce an extract phase soluble in the selective solvent and after cooling the extract phase to cause separation of the most insoluble fractions from the solvent and fractions remaining dissolved, these insoluble fractions and fractions remaining dissolved in the solvent are contacted in a subsequent extraction in the manner set forth above, in order that the said insoluble fractions may function as a wash oil to remove valuable constituents of the low solubility paraffinic type from the remaining extract phase. These valuable constituents dissolve in the wash oil and are thus recovered from the extract phase.

It is, therefore, an object of our invention to extract hydrocarbon mixtures containing paraffinic and non-paraffinic fractions in a plurality of stages in which fresh extracting medium is added in each successive stage, and there is removed from each successive stage a raffinate and solvent containing dissolved fractions; to cool the solvent solution of extracted fractions and separate oil fractions therefrom; to introduce the oil separated by cooling the solvent into the lower zone of the next succeeding extraction stage and to introduce the cooled solvent containing the remaining dissolved fractions into the intermediate zone of the next extraction stage.

Furthermore, it is an object of our invention to extract hydrocarbon mixtures containing paraffinic and non-paraffinic fractions in a plurality of stages in which fresh extracting medium is introduced in each successive stage and there is withdrawn therefrom a raffinate and solvent containing dissolved fractions. The solvent containing the dissolved fractions is cooled to separate oil fractions insoluble in said solvent at the lowered temperature. The cooled solvent and undissolved fractions are separated, the insoluble fraction is introduced into the lower zone of the next succeeding extraction stage and the solvent and remaining dissolved fractions are directed into two streams, one of which is introduced into the intermediate zone of the next succeeding stage and the other stream is returned to the intermediate zone of the preceding extraction stage.

Figure 1 is a schematic arrangement of one form of apparatus which we may employ to carry out our process.

Figure 2 is another schematic arrangement of apparatus which we may employ to carry out our process.

Referring more particularly to Figure 1, extracting medium, from a source not shown, is introduced into the upper zone of column 3 through pipe 1. The raw stock to be extracted is introduced into the lower zone of column 3 through pipe 2. The extracting medium in column 3 being heavier than the raw stock passes downward through the ascending column of oil. In its passage downward through the column 3 the extracting medium dissolves certain non-paraffinic hydrocarbons present in the oil. The oil from which the non-paraffinic fractions have been removed is removed from column 3 through line 4 as a first raffinate.

The solvent and dissolved fractions are re-

moved from the lower zone of column 3 through line 5, valve 6, line 7, pump 8 and line 9 to cooler 11 where the temperature of the solvent and dissolved fraction is lowered sufficiently to cause a portion of the dissolved fractions to be forced out of solution. The cooled mass in cooler 11 is then passed through line 10 to settling chamber 11 where the light insoluble fractions rise to the top, are removed through line 17 and are introduced into the lower zone of extraction column 18. The relatively heavy solvent containing the remaining dissolved fractions is removed from the bottom of settling chamber 11 through line 12, valve 13, line 14, pump 15 and line 16 and then introduced into the intermediate zone of column 18. The temperature of extraction in column 18 is relatively lower than the temperature in column 3.

Fresh solvent is introduced into the upper zone of column 18 through line 19. The temperature of this solvent is usually approximately the same as that of the fractions introduced into the column through lines 16 and 17. The descending heavy solvent in column 18 dissolves a portion of the fractions in the ascending column of oil 25 which finally rises to the top of the column and is removed through line 20 as a second raffinate.

The solvent and dissolved fractions settle to the bottom of column 18 and are removed through line 21, valve 22, line 23, pump 24 and line 25 to cooler 26 where the temperature of this solution is lowered sufficiently to cause a portion of the hydrocarbons to be forced out of solution. The cooled mass in cooler 26 is then passed through line 27 to settling chamber 28 where the insoluble relatively light oil fractions rise to the top, are withdrawn through line 29 and introduced into the lower zone of column 30. The solvent containing the remaining dissolved fractions settles out in chamber 28 and is passed through line 31, valve 32, line 33, pump 34 and line 35 into the intermediate extraction zone of column 30.

Fresh solvent is introduced into the upper zone of column 30 through pipe 40 at a temperature substantially the same as that of the fractions introduced into column 30 through lines 29 and 35.

The relatively heavy solvent in column 30 gravitates downward through the ascending column of oil. In its path downward the solvent dissolves certain non-paraffinic fractions from the oil. The purified oil finally rises to the top of column 30 and is removed as a third raffinate through line 36. The solvent containing dissolved fractions is removed from column 30 through line 37, valve 38 and line 39 to distillation means where the solvent is recovered from the extract. The raffinates recovered from lines 4, 20 and 36 are also distilled to remove any remaining dissolved solvent contained therein. These raffinates may then be given any further treatment as may be necessary for the production of finished oils, such as acid, alkali and/or clay treatment.

As will be noted the fractions introduced into columns 18 and 30, respectively, through lines 16 and 35 aid the fresh solvent introduced through lines 19 and 40 in removing non-paraffinic oils from the ascending column of oil introduced into the lower zones of these columns.

Referring more particularly to Figure 2, the stock to be extracted enters column 52 through line 50. The extraction medium enters column 52 through line 51. The relatively heavy solvent passes downward through the ascending column 75.

of relatively light oil. During its passage downward through column 52 the solvent dissolves the most soluble fractions present. The ascending column of oil finally rises to the top of the column 5 and is removed as a first raffinate through line 53. The solvent containing dissolved fractions is removed through line 54, valve 55, line 56, pump 57 and line 58 to cooler 59 where its temperature is lowered sufficiently to cause a portion of the dissolved oil to be forced out of solution. The cooled mass in cooler 59 then passes through line 60 to settling chamber 61 where the relatively light insoluble oil fractions rise to the top and are conducted through line 62 into the lower 10 zone of extraction chamber 63. The solvent containing the remaining dissolved fractions is removed from settling chamber through line 64. From line 64 the stream of solvent and dissolved fraction is divided; one stream passes through 15 valve 70, pump 71 and line 72 and is introduced into the intermediate zone of extraction column 63. The other stream passes through valve 65, pump 66, and line 67 into heater 68 where its temperature is raised substantially equal to that of the stock and solvent introduced into column 25 52 through lines 50 and 51. From heater 68 the solvent passes through line 69 into the intermediate zone of extraction column 52.

Fresh solvent is introduced through line 74 into 30 column 63 at a temperature substantially the same as that of the oil and extraction medium entering this column through lines 62 and 72. The fresh solvent, along with the partially contaminated solvent in column 63 move downward 35 through the ascending column of oil and dissolve a portion of the undesirable components present. The ascending column of oil in column 63 finally is removed through line 73, as a second raffinate.

The solvent containing dissolved fractions is 40 removed from column 63 through line 75, valve 76, line 77, pump 78 and line 79 to cooler 80 where its temperature is lowered sufficiently to cause separation of a portion of the dissolved oil. The cooled mass then passes from cooler 80 through line 81 into settling chamber 82, where the relatively light insoluble fractions rise to the top and are removed through line 83 into the lower zone of extraction column 84. The 45 relatively heavy solvent containing the remaining dissolved fractions settles out of chamber 82 and is removed through line 85. Here the solvent and remaining dissolved fractions are divided into two streams. One stream passes through valve 86, pump 92 and line 93 into the intermediate zone of extraction column 84. The other stream is removed through valve 87, pump 88 and line 89 into heater 90 where its temperature is raised to a point substantially the same as that of the 50 solvent entering chamber 63 through lines 72 and 74. The heated solvent containing dissolved fractions then passes from heater 90 through line 91 into the intermediate zone of column 63. The material introduced through line 91 into extraction column 63 is less contaminated with dissolved fractions than the material introduced in this column through line 72. Furthermore, the material introduced into column 63 through line 72 is a contaminated solvent with respect to 55 the solvent introduced through line 74. These three solvents introduced through lines 74, 72 and 91, respectively, countercurrently contact the rising column of oil introduced through line 62 in the inverse order of their degree of purity, i. e., the oil is contacted with the most contaminated solvent first and finally with fresh solvent.

Likewise the rising oil column in column 52 introduced through line 51 is contacted first with contaminated solvent introduced through line 68 and finally with fresh solvent introduced through line 50.

Fresh solvent is introduced through line 98 into the upper zone of column 84 at a temperature substantially the same as the oil fraction introduced into this column through line 83 and the 10 contaminated solvent introduced through line 93.

The ascending column of oil in column 84 is first contacted with the contaminated solvent introduced through line 93 and finally with the fresh solvent introduced through line 98 after 15 which it is removed through line 94 as a third raffinate. The solvent containing the dissolved fractions is removed from column 84 through line 95, valve 96 and line 97 to distillation means, not shown, where the extract is separated from 20 the solvent.

The raffinates recovered through lines 53, 73 and 94 may be given any further treatment necessary for the production of finished oils; such as acid, alkali and/or clay treatment.

As solvents we may employ liquid sulphur dioxide, selenium oxychloride, aniline, nitrobenzene, B B' dichlorethyl ether, furfural or mixtures thereof.

As an example of one method of carrying out 30 our invention a lubricating oil fraction containing both paraffinic and nonparaffinic fractions is introduced into column 3 through line 2 at an approximate temperature of 110° F. B B' dichlorethyl ether is introduced into the upper zone 35 of column 3 through line 1 at a temperature of about 110° F. A first raffinate is withdrawn from column 3 through line 4. Solvent containing dissolved fractions is withdrawn from the bottom of column 3 through line 5 and passed through 40 cooler 41 where its temperature is lowered to approximately 80° F. The cooled mass then passes from cooler 41 to settling chamber 11 where the oils forced out of solution by cooling rise to the top and are introduced into the lower zone 45 by column 18 through line 17. The solvent containing the remaining dissolved fractions is withdrawn from the bottom of chamber 11 and introduced into the intermediate zone of extraction column 18. B B' dichlorethyl ether is introduced 50 into column 18 through line 19 at a temperature of about 80° F. A second raffinate is withdrawn through line 20 from column 18. The B B' dichlorethyl ether containing dissolved fractions is withdrawn from column 18 through line 55 21 and passed to cooler 26 where its temperature is lowered to approximately 40° F. At this temperature a portion of the dissolved oil is rendered insoluble. The cooled mass passes from cooler 26 to settling chamber 28 where the relatively light 60 insoluble oil rises to the top and is withdrawn through line 29 and introduced into the lower zone of extraction column 30.

The solvent containing the remaining dissolved 65 fractions settles to the bottom of chamber 28, is withdrawn and introduced through line 35 into the intermediate zone of column 30. B B' dichlorethyl ether at a temperature of about 40° F. is introduced through pipe 40 into the upper zone of column 30. The oil introduced in column 30 through line 29 rises and is countercurrently extracted by the stream of solvent introduced through line 40 and the contaminated solvent introduced through line 35. The oil 70 75

from which the undesirable fractions have been removed is finally withdrawn through line 36.

The solvent containing the dissolved fractions is removed through line 39 and sent to distillation means where the B B' dichlorethyl ether is separated from the extracted fractions.

While the example is specifically directed to extraction in stages operating at successively lower temperatures it is to be understood that 10 all of the extraction stages may be operated at the same temperature and in some cases it may be desired to operate each successive stage at an increasing temperature, especially where different solvents are introduced in the successive 15 stages.

When it is desired to operate all of the extraction stages at the same temperature or each successive extraction stage at an increasing temperature it then becomes necessary to interpose 20 heaters in lines 16, 17, 29 and 35 of Fig. 1 and lines 62, 72, 83 and 93 of Fig. 2. By the use of these heaters the fractions passing to all of the extraction stages may be heated to the same temperature or if desired the temperature of the 25 fractions passing to the successive extraction stages may be increased at each stage.

This same effect may be produced by closing valves 13 and 32 of Fig. 1 and passing the solvent and dissolved fractions to the respective extraction

30 stages 18 and 30, in which case coolers 41 and 26 merely function as flow lines and the solvent and dissolved fractions pass to each successive extraction stage at substantially the same temperature. When it is desired to operate each 35 successive extraction stage at an increasing temperature, 41 and 26 of Fig. 1 operate as heaters and the solvent and dissolved fractions from the bottom of column 3 are increased in temperature before passing via line 17 into column 18; and 40 in the same manner the solvent and dissolved fractions withdrawn from column 18 are increased in temperature before passing via line 29 into column 30. When 41 and 29 of Fig. 1 function as heaters, valves 13 and 32 remain closed.

45 The same solvent may be employed in each successive stage of the extraction or if desired different solvents may be introduced in each successive stage as for example in Figure 1 the initial solvent introduced through line 1 may be liquid 50 sulphur dioxide, the solvent introduced in lines 19 and 40 may be B B' dichlorethyl ether or any other solvent which will separate the types of raffinates desired in each of the successive stages.

The foregoing example is merely illustrative of 55 one method of carrying out our invention and is not to be construed as limiting the invention which we claim.

We claim:

1. A process for separating a hydrocarbon oil 60 mixture into a plurality of fractions which comprises extracting said oil with a solvent into an insoluble fraction and fractions dissolved in said solvent, separating the insoluble fraction from the fractions dissolved in said solvent, cooling said 65 solvent containing dissolved fractions to separate a fraction insoluble in said cooled solvent, removing said insoluble fraction from said cooled solvent containing the remaining dissolved fractions, subsequently passing said cooled solvent containing dissolved fractions and said cooled fraction insoluble in said cooled solvent to a later extraction stage and extracting said cooled insoluble fraction with said cooled solvent containing dissolved fractions into a plurality of fractions.

75 2. A process for separating a hydrocarbon oil

mixture into a plurality of fractions which comprises extracting said oil with a solvent into a fraction insoluble in said solvent and fractions soluble in said solvent, separating said insoluble fraction from said solvent and dissolved fractions, 5 cooling said solvent and dissolved fractions to separate a further fraction, removing said last mentioned fraction from said cooled solvent containing the remaining dissolved fractions, subsequently passing said fraction separated from said cooled solvent to a later extraction stage, and extracting said fraction passed to said later stage with said cooled solvent containing the remaining dissolved fractions.

3. A process for separating a hydrocarbon oil 15 mixture into a plurality of fractions which comprises extracting said oil with a solvent into a fraction insoluble in said solvent and fractions soluble in said solvent, separating said insoluble fraction from said solvent and dissolved fractions, 20 cooling said solvent and dissolved fractions to separate a further fraction, removing said last mentioned fraction from said cooled solvent containing the remaining dissolved fractions, subsequently passing said fraction separated from said cooled solvent to a later extraction stage, and extracting said fraction passed to said later stage with fresh solvent and said cooled solvent containing the remaining dissolved fractions.

4. A process for separating a hydrocarbon oil 30 mixture into a plurality of fractions which comprises extracting said oil with a solvent, separating a fraction insoluble in said solvent from the solvent and remaining dissolved fractions, cooling the solvent containing dissolved fractions to separate a fraction insoluble in said cooled solvent, 35 removing said insoluble fraction from said cooled solvent containing the remaining dissolved fractions, subsequently passing said fraction insoluble in said cooled solvent to a later extraction 40 stage and extracting said cooled insoluble fraction with fresh solvent and said cooled solvent containing remaining dissolved fractions.

5. A process for separating a hydrocarbon oil 45 mixture into a plurality of fractions which comprises extracting said oil with a solvent, separating a fraction insoluble in said solvent from the solvent and remaining dissolved fractions, cooling the solvent containing remaining dissolved fractions to separate a fraction insoluble in said 50 cooled solvent, removing said insoluble fraction from said cooled solvent containing the remaining dissolved fractions, subsequently passing said fraction insoluble in cooled solvent to a later extraction stage, extracting said cooled insoluble fraction in said later stage with fresh solvent and a portion of said cooled solvent containing dissolved fractions, heating the remaining portion of cooled solvent and dissolved fractions and returning said heated solvent and dissolved fractions 55 to an earlier extraction stage.

6. A process for the separation of oil from a selective solvent containing dissolved fractions which comprises cooling said solvent and dissolved fractions to separate a fraction insoluble 65 in said cooled solvent, removing said insoluble fraction from said cooled solvent containing the remaining dissolved fractions, passing said insoluble fraction separated from said cooled solvent and remaining dissolved fractions to a later 70 extraction stage and extracting said insoluble fraction passed to said later stage with said cooled solvent containing the remaining dissolved fractions.

7. A process for the separation of oil from a 75

- selective solvent containing dissolved fractions which comprises cooling said solvent and dissolved fractions to separate a fraction insoluble in said cooled solvent, removing said insoluble fraction from said cooled solvent containing the remaining dissolved fractions, passing said insoluble fraction separated from said cooled solvent and remaining dissolved fractions to a later extraction stage and extracting said insoluble fraction passed to said later stage with fresh solvent and with said cooled solvent containing the remaining dissolved fractions.
8. A process for separating a hydrocarbon oil mixture into a plurality of fractions which comprises extracting said oil with a solvent, separating a fraction insoluble in said solvent from the solvent and the remaining dissolved fractions, cooling the solvent containing the remaining dissolved fractions to separate a fraction insoluble in said cooled solvent, removing said last mentioned insoluble fraction from said solvent containing the remaining dissolved fractions, passing said fraction insoluble in cooled solvent to a later extraction stage, extracting said cooled insoluble fraction in said later stage with a portion of said cooled solvent containing dissolved fractions and returning the remaining portion of cooled solvent and dissolved fractions to an earlier extraction stage.
9. A process for separating a hydrocarbon oil mixture into a plurality of fractions which comprises extracting said oil with a solvent, separating a fraction insoluble in said solvent from the solvent and the remaining dissolved fractions, cooling the solvent containing the remaining dissolved fractions to separate a fraction insoluble in said cooled solvent, removing said last mentioned insoluble fraction from said solvent containing the remaining dissolved fractions, passing said fraction insoluble in cooled solvent to a later extraction stage, extracting said cooled insoluble fraction in said later stage with fresh solvent and a portion of said cooled solvent containing dissolved fractions, heating the remaining portion of cooled solvent and dissolved fractions and returning said heated solvent and dissolved fractions to an earlier extraction stage.
10. A process for the separation of oil from a selective solvent containing dissolved fractions which comprises cooling said selective solvent containing dissolved fractions to separate a fraction insoluble in said cooled solvent, removing said insoluble fraction from the cooled solvent and remaining dissolved fractions, passing said insoluble fraction to a later extraction stage, extracting said cooled insoluble fraction in said later stage with a portion of said cooled solvent containing dissolved fractions and returning the remaining portion of cooled solvent and dissolved fractions to an earlier extraction stage.
11. A process for the separation of oil from a selective solvent containing dissolved fractions which comprises cooling said selective solvent containing dissolved fractions to separate a fraction insoluble in said cooled solvent, removing said insoluble fraction from the cooled solvent and remaining dissolved fractions, passing said insoluble fraction to a later extraction stage, extracting said cooled insoluble fraction in said later stage with fresh solvent and a portion of said cooled solvent containing dissolved fractions and returning the remaining portion of cooled solvent and dissolved fractions to an earlier extraction stage.
12. A process for the separation of oil from a selective solvent containing dissolved fractions which comprises cooling said selective solvent containing dissolved fractions to separate a fraction insoluble in said cooled solvent, removing said insoluble fraction from the cooled solvent and remaining dissolved fractions, passing said insoluble fraction to a later extraction stage, extracting said cooled insoluble fraction in said later stage with fresh solvent and a portion of said cooled solvent containing dissolved fractions, heating the remaining portion of cooled solvent and dissolved fractions and returning said heated solvent and dissolved fractions to an earlier extraction stage.
13. A process for separating a hydrocarbon oil mixture into a plurality of fractions which comprises extracting said oil with a selective solvent, separating a fraction insoluble in said solvent from the selective solvent and dissolved fractions, commingling said selective solvent and dissolved fractions with a wash oil and removing the wash oil containing dissolved fractions from said solvent and fractions remaining dissolved therein.
14. A process according to claim 13 wherein the wash oil is a fraction separated as an insoluble fraction from the selective solvent solution of dissolved oil fractions by cooling said solution and separating said fraction insoluble at the lowered temperature.
